(57) **CLAIM**

The ornamental design for a squeezable container for liquid and lotion dispensing, as shown and described.

DESCRIPTION

FIG. 1 illustrates a front perspective view of an embodiment of the squeezable container for liquid and lotion dispensing showing my new and ornamental design; the opposite side being a mirror-image thereof;

FIG. 2 illustrates a side view, the opposite being a mirror-image thereof;

FIG. 3 illustrates a bottom view thereof;

FIG. 4 illustrates a front view, partly in section, showing a cover portion attached thereto; and,

FIG. 5 illustrates a perspective exploded view showing all of the components thereof.
